HERMON L. VAN VALKENBURG, OF WAUWATOSA, WISCONSIN, ASSIGNOR, BY MESNE ASSIGNMENTS, TO SQUARE D COMPANY, OF DETROIT, MICHIGAN, A CORPORATION OF MICHIGAN

MOTOR-CONTROL SYSTEM

Application filed October 19, 1926. Serial No. 142,626.

My invention relates to motor control systems, and while it may be made of general application for use in connection with machines which are to be periodically reversed, it is peculiarly adapted for the control of laundry machines in which the basket rotates first in one direction for a certain period and then in the opposite direction for a period. One of the objects of the invention is to provide a unitary system in which the motor, the machine and the controller are all geared together, the controller both causing the reversal of the machine and reversing with it. This obviates the need of a separate motor for rotating the drum. Another object is to provide a type of apparatus in which the controller may overrun without harm thereby doing away with the need of a slip clutch or similar protective device. A further object is to provide simple means by which the machine may be jogged or "inched" so as to bring the basket to convenient position for loading and unloading. Still another object is to provide simple and efficient apparatus in which the motor current is handled entirely by means of main switches so that the controller does not have to carry a heavy current.

I accomplish these objects by the mechanism illustrated in the accompanying drawings, in which

Figure 1 is a general view largely diagrammatic in its nature showing the general assembly, including the washing machine, motor, main switch, drum controller in developed form, and the hand switches and push buttons.

Figures 2 to 6 are diagrammatic views showing the drum controller in different positions.

Like numerals denote like parts throughout the several views.

In the illustrated form the washing machine has a cylindrical basket 10 journaled in a frame 12 and enclosed within a tub or container 14 in the usual manner. The basket has a door 16 through which the machine may be loaded and unloaded. Power is supplied by a motor M connected to the basket by an appropriate train of gears 20. To one of the

gears of the train there is fastened a shaft 22 provided with a pulley 24 connected by a belt 26 to another pulley 28 fastened to a shaft 30 provided with a worm 32 which meshes with a worm gear 34 fastened to the main shaft 36 of the drum controller. 55

In the drawings the controller is shown in developed form, that is in the flat. The drum 38 is provided with a reversing segment R, a forward holding segment f and a backward holding segment g. In line with the segment R at one side are two fingers 40, 42 and at the other side are two fingers 44, 46. In line with the segment f are two contact fingers 48, 50, and in line with the segment g are two contact fingers 52, 53. The contact fingers are stationary while the segments R, f, g rotate with the drum in the usual manner. 60 65

The drum controller just described constitutes the master switch. I will now describe the main switches through which the main energizing currents are carried to the motor: 70

In the form illustrated a three-phase system is employed having three main conductors A, B, C. These are connected to stationary contacts 60, 62, 64 adapted to be engaged by switch arms 61, 63, 65 respectively. These arms are controlled by a rod 66 which is longitudinally movable and is urged by a spring 68 to hold the switch arms in open position as shown in Fig. 1. For identification this will be termed the "forward" main switch. The arm 61 is connected by a conductor 70 to a conductor 71 constituting one of the motor leads. Arm 63 is connected by a conductor 72 to a conductor 73 which constitutes another of the motor leads, and arm 65 is connected by a conductor 74 to a conductor 75 which constitutes the third motor lead. For operating the machine in the reverse direction there is what may be termed a "backward" or reverse main switch. This includes three switch arms 76, 77, 78 which are connected respectively to the conductors 75, 73, 71. The arms are adapted to engage contacts 80, 81, 82 respectively which are connected by conductors 83, 84, 85 to the contacts 60, 62, 64 respectively. Said arms are op- 75 80 85 90 95 100

erated by a switch rod 86 which is urged by a spring 88 to hold the switch arms open.

Switch arm 66 is controlled by a winding F, one end of which is connected by a conductor 90 to the main supply conductor A. A movable core 91 is located within the field of winding F and is connected to rod 66 with the result that when the winding is energized, the switch arms 61, 63, 65 will close. The other end of winding F is connected by a conductor 92 to a stationary contact 93 which is connected by a conductor 94 to the finger 40 on the drum. The circuit through the winding may be completed through the reversing segment R and finger 42 by a conductor 96 which is connected to a conductor 97 connected to the finger 48. Said finger is connected to the finger 50 by the holding segment f. A conductor 98 connects finger 50 with a conductor 99 which leads to the switch terminal 100 of the hand-operated change switch E. The other terminal 101 of this switch is connected by a conductor 102 to a conductor 103 which is connected to a hand-operated service switch D. The stationary contact 104 of this service switch is connected by a conductor 105 to the main line conductor C.

The switch rod 86 is controlled by a winding G which controls a movable core 110 fastened to the rod in such manner that when the winding is energized the switch arms 76, 77, 78 will close. A conductor 112 connects one end of winding G to the conductor 83. At the opposite end the circuit through the winding is completed by a conductor 113 which leads to a contact 114 which is connected to a conductor 115 which leads to the finger 44. The reversing segment R may connect the finger 44 to the finger 46 which is connected by a conductor 116 to a conductor 118 which is connected to finger 53. This finger may be connected by holding segment g which is connected to conductor 99 which leads to the main supply conductor C in the manner previously described. The forward main switch rod 66 is connected to and operates a holding switch 120 which is connected to conductor 96 and is adapted to engage contact 93. The backward switch rod 86 is connected to and operates a holding switch 122 which is connected to conductor 118 and is adapted to engage contact 114. These holding switches 120, 122 are closed by the switch rods at the same time that the main supply switches close.

Now to describe the switches by which the motor may be started or by which it and the basket of the washing machine may be jogged or "inched" when necessary for loading or unloading: For inching, the drum controller is put out of service by opening the change switch E and then closing the circuit for one or more short periods through the motor to cause it to rotate the required amount. This

is done by momentarily closing the forward or backward main switch, as the case may be. To rotate the motor backwards the operator closes the normally open push button 130 which is connected to the conductor 102 and is adapted when closed to engage the contact 131 which is connected by the conductor 132 to conductor 115.

To rotate the motor forward the operator closes the normally open push button 140 which is connected to the conductor 103 and is adapted when closed to engage a contact 142 which is connected by a conductor 144 to conductor 94.

Operation.—Let it be assumed that the motor is at rest in its mean position and the various switches open and the drum controller in approximately neutral position, all as shown in Figure 1. If now the operator wishes to start up the motor and cause the machine to operate automatically, in distinction to "inching", he closes service switch D and change switch E and presses one of the push buttons 130 or 140. It is immaterial in which direction the machine starts to rotate, and to conform to the selected diagrams let it be assumed that he wishes the machine first to rotate backward. He pushes button 130 to closed position whereupon the winding G is energized and closes the switch arms 76, 77, 78, which energizes the motor and causes it to rotate in what may be termed a backward direction.

The winding is energized as follows: from supply conductor A to contact 60, to conductor 83, to conductor 112, to winding G, to conductor 113, contact 114, conductors 115 and 132, contact 131, push button 130, conductor 103, switch D, contact 104, conductor 105 and main supply conductor C. The movement of the switch rod 86 to closed position closes the holding switch 122 and thereafter the winding G is kept energized as follows: from supply conductor A to contact 60, conductors 83 and 112, to winding G, thence by conductor 113, contact 114, holding switch 122, conductor 118, finger 53, segment g, finger 52, conductor 99, contact 100, switch E, conductors 102, 103, switch D, and conductor 105 to main conductor C. As the motor rotates it displaces the drum from the mean position shown in Figure 1 toward the left to the position shown in Figure 2 where the segment g has moved out of engagement with the fingers 52, 53, thus opening the circuit through the winding G and permitting spring 88 to open the main switch and incidentally open the holding switch 122.

The motor current is now cut off but the motor will continue to drift and further displaces the drum controller to the position shown in Fig. 3 in which the reversing segment R engages the fingers 40, 42 which completes the circuit through the forward winding F in the following manner, it being un-

derstood that the holding segment *f* still remains in engagement with the fingers 48, 50; from the supply conductor A to conductor 90 to winding F, thence through conductor 92, contact 93, conductor 94, finger 40; segment R, finger 42, conductors 96 and 97, finger 48, segment *f*, finger 50, conductors 98, 99, switch E, conductors 102 and 103, switch D, and conductor 105 to the supply conductor C. As a result of energizing the winding F the forward switch arms 61, 63, 65 close and supply the motor, the phase relation being changed and the motor rotating in the opposite or forward direction. The closing of the forward switch incidentally closes the holding switch 120, with the result that thereafter the winding F is kept energized through the following circuit:

From conductor A to conductor 90 to winding F, thence to conductor 92, contact 93, holding switch arm 120, conductors 96 and 97, finger 48, segment *f*, finger 50, conductor 98, conductor 99, switch E, conductors 102 and 103, switch D and conductor 105 to the supply conductor C.

As the motor is now reversed it will cause the washing machine and the drum controller to rotate in the opposite direction and the controller to move toward the right from the position shown in Figure 3 to the position shown in Figure 4. This latter figure shows the drum after it has rotated the major portion of its normal travel. The segment *f* has left the fingers 48, 50, thus opening the circuit through the winding F and incidentally opening the holding switch 120. The spring 68 now opens the forward switch arms 61, 63, 65, thus cutting off the motor, which however continues to drift until the position shown in Figure 5 is reached, where the reversing segment R has reached the fingers 44, 46. The segment *g*, however, still remains in contact with the fingers 52, 53. Thereupon the motor will begin to work for the winding G will be energized as follows: from the supply conductor A, contact 60, conductors 83 and 112 to the winding G, thence through the conductor 113, contact 114, conductor 115, finger 44, segment R, finger 46, conductors 116 and 118, finger 53, segment *g*, finger 52, conductor 99, switch E, conductors 102 and 103, switch D, and conductor 105 to the main line conductor C. The closing of the main switch closes the holding switch 122, which will keep the winding G energized in the manner previously described. Thus it will be seen that the motor is caused to rotate alternately in opposite directions for a predetermined number of rotations and the action will be entirely automatic after the push button has been pressed for starting the system.

It will be noted that either of the push buttons 130 or 140 may be employed for starting up the apparatus after the switches D and

E have been closed. The closing of the switch 140 will cause the energization of winding F to start the motor in a forward direction in the following manner: from the supply conductor A to the conductor 90 and coil F; thence through the conductor 92 to the contact 93, conductors 94 and 144, contact 142, switch 140, conductor 103, switch D, and conductor 105 to the supply conductor C. After this coil F is once energized it closes the holding switch 120 which thereafter keeps the coil energized so long as the segment *f* remains in contact with the fingers 48, 50.

Assume now that the washing operation is complete, and that the washing machine is to be unloaded. Ordinarily it will be necessary to rotate the basket forward or backward a greater or less distance, as the case may be, to bring the door 16 to proper position for inserting or removing the clothing, or other goods to be treated. This supplemental rotary movement or "inching" will be accomplished as follows: The operator will first open the change switch E as a preliminary to changing from automatic to hand control. Suppose that he wishes the machine then to move forward a short distance. He will press the push button 140 which will energize the forward coil F as follows:

From the supply conductor A to the conductor 90, to coil F, thence through conductor 92 to contact 93, conductor 94, conductor 144, contact 142, switch 140, conductor 103, switch D, conductor 105 through the main supply conductor C. Energizing the winding will close the main switch arms 61, 63, 65. The operator will hold the hand switch closed only for a moment, which will jog the motor forward. If the movement is insufficient the action can be repeated. If instead of desiring the machine to move forward the operator wishes it to move backward, he will press the push button 130 which will energize the backward coil G as follows: from the supply conductor A to contact 50, to conductors 83 and 112, to the coil, thence through conductor 113, contact 114, conductors 115 and 132, contact 131, switch 130, conductor 103, switch D and conductor 105 to the main conductor C. This switch 130 will be held closed only momentarily for one or more times although after an operator becomes experienced he may be able to estimate the amount of time the push button switch must be held closed to cause the desired movement of the basket.

In the form shown, the drum controller is designed to rotate about 180 degrees, first in one direction and then in the other. There may be occasions, however, when the motor will cause the drum controller to overrun. For example, if the operator cuts off the current by opening the switch E at a moment when the parts are in a position such as that illustrated in Figure 4 where the reversing

segment R is near the end of its travel, but upon reaching the fingers 44, 46 does not have the benefit of the reverse current to stop the motor. In such event the motor is apt to drift for a considerable distance, for instance, to a position such as that shown in Figure 6. But no harm will be done, for the motor may be jogged independently of the drum controller, that is, by using the push buttons 130 or 140 in the manner already described. If the operator wishes to recommence automatic operation all he will have to do will be to hold one of the push buttons closed long enough to cause one of the segments f or g to engage their cooperating fingers. Thus the drum controller is not required to have any definite stopping point and there is no need of a slip clutch or similar device for protecting the apparatus from wrecking itself.

Having thus described my invention, what I claim as new and desire to secure by Letters Patent is:

1. In a system for driving and periodically reversing a rotatable body, an electric motor for driving said body, magnetic switches, one for causing the motor to rotate forwardly and the other backwardly, a rotatable controller connected to said body to rotate therewith, the normal zone of operation of the controller being less than a complete revolution, and means controllable at will and independent of the controller for inching the motor to bring the controller back into the zone of operation in case it should over-travel.

2. A system for driving and periodically reversing a rotating body having an electric motor connected to said body for driving it, a pair of magnetic switches, one for causing the motor to rotate forward and the other backward, a drum controller for operating said switches, means for rotating the drum first in one direction and then in the opposite direction in synchronism with the rotating body, the drum having a normal zone of operation which is less than a complete revolution, and an inching switch arranged in parallel with the drum controller for holding a main switch closed and thereby causing rotation of the motor independently of the drum whereby if the drum has rotated past its zone of operation the inching switch can be employed to bring it back.

3. In a reversible motor controlling system, a motor, a switch for causing the motor to rotate forwardly, a second switch for causing the motor to rotate backwardly, operating circuits for said switches and a rotatable drum controller mechanically connected to the motor for reversing rotation therewith, said controller having a pair of holding segments for maintaining each and operating circuit of a said switch, said segments being arranged circumferentially of the controller, the opposed ends of the segments being arranged in overlapping and in

spaced relationship, and a reversing segment arranged in the circumference of said controller at a point opposite the space between the spaced ends of said holding segments.

4. In an electric power system for driving and periodically reversing a rotating body, a motor connected to said body for driving it in either direction, a main switch for operating the motor forwardly, a second switch for reversing the motor and a movable controller connected to the rotating body, and movable forwardly and backwardly in synchronism with it, a circuit for operating said main switch, and a second circuit for controlling said reversing switch, said controller having a pair of elongated holding segments with spaced apart ends and arrangeable, each in one of said operating circuits to close the same, and a shorter reversing segment rotating intermediate the ends of the holding segments for normally energizing one or the other of said operating circuits, the operation of said reversing segment depending upon which of the hold circuits is in operating position at the time.

In witness whereof, I have hereunto subscribed my name.

HERMON L. VAN VALKENBURG.
